UNITED STATES PATENT OFFICE.

ERNEST F. RUECKERT, OF PROVIDENCE, RHODE ISLAND.

FORK OR TONGS.

1,168,115.

Specification of Letters Patent.

Patented Jan. 11, 1916.

Application filed May 20, 1915. Serial No. 29,380.

To all whom it may concern:

Be it known that I, ERNEST F. RUECKERT, citizen of the United States, residing at Providence, in the county of Providence and 5 State of Rhode Island, have invented a new and useful Fork or Tongs, of which the following is a specification.

This invention relates to an improvement in forks or tongs, and more particularly that 10 type of tongs to be used for lifting articles, such as sugar, pickles, olives and the like.

The object of the invention is to provide novel means for fastening the spring to the tube or casing so as to dispense with the use 15 of solder in the construction of the tongs.

The invention consists in certain novel features of construction and combination of parts which will be hereinafter described and pointed out in the claim.

20 It is to be understood that many slight changes may be made in the form and arrangement of the several parts described without departing from the spirit and scope of the invention, and hence I do not wish to 25 be limited to the exact construction herein set forth.

In the accompanying drawings, Figure 1 is a view partly in elevation and partly in section of the invention. Fig. 2 is an enlarged detail sectional view of the manner 30 of mounting the spring, and its connection to the rod and to the tubular casing. Fig. 3 is a sectional view on the line 3—3 of Fig. 2. Fig. 4 is a perspective view of the plug or 35 bushing, and Fig. 5 is a detail perspective view of an end of the tubular casing.

A represents the tube or casing in which a rod 1 is slidably mounted. This tube or casing is split along one side as shown in 40 Fig. 1, the meeting edges of the split portion coming together in a close joint, but not soldered. One terminal of the rod is provided with a slot 3 for supporting the flexible jaws 2. The jaws 2 are preferably made 45 from a single piece of material and are supported at their inner ends by the looped or slotted end 3 of the rod, the jaws being connected to the rod by passing one of the jaws through the loop 3. The outer ends of the 50 jaws are preferably bowed, as at 4, so that the jaws cannot be drawn entirely within the tubular casing A, but as the jaws are drawn into the casing the bowed faces of the jaws will be drawn together for clamping or grasping the article therebetween.

A plug or bushing 5 is mounted in the tube A through which the rod 1 moves and is guided in its movements. The plug 5 is provided with a head or flange 6 which extends over the upper end of the tube for insuring the maintenance of the plug in the tube. One side or wall of the plug 5 is cut away to produce a straight or flat surface 7, for forming a space between the plug and the inner wall of the tube. 60 65

A coil spring 8 is connected to the rod 1 by wrapping one end of the wire closely and tightly to the rod. The other terminal of the spring extends into the space formed between the plug 5 and the casing and is 70 then bent at right angles, as at 9. The bent terminal 9 of the spring is received in a recess 10, formed in the tube A, thereby locking the spring to the casing and rod. The plug 5 will be forced into position after the spring has been inserted in the slot or recess 10. 75

A ring or disk 11 is mounted upon the tube and is provided with an annular flange 12 which is spun or caused to frictionally engage the wall of the tube for closing the recess 10. The disk is further maintained in place by the head 6 of the plug 5 which engages the upper surface of the disk or ring.

The rod 1 is provided with a knob 13 so that in the operation of the tool or tongs the knob is grasped by the thumb and the tube placed between the first and second fingers which will grasp the ring 11 whereby the jaws may be actuated for grasping or releasing an article.

The opening of the jaws by forcing the rod 1 into the tube A is always against the tension of the spring 8, so that after the tongs are placed about the article to be grasped the thumb can be removed from the knob 13 and the spring will cause the jaws to be moved within the tubular member for grasping the article.

When the plug 5 is forced into the tube A it causes an impingement of the terminal of the spring between the wall of the tube and the flat surface 7 of the plug for confining the spring in place.

105
What is claimed is—

In combination with a tube having a recess in the inner end thereof, a rod slidably mounted therein, jaws connected to the rod and extending from the outer end of the

tube, a coiled spring mounted on the rod, and having its outer portion coiled tightly about the rod and its inner terminal bent and engaged with the said recess, a plug 5 having an opening through which the rod passes and closing the inner end of the tube and bearing against the inner terminal of the spring and holding it in position, and a disk mounted upon the tube on the outside 10 of the said recess and closing the latter, said

plug having a head which overlaps the end of the tube and engages the disk.

In testimony, that I claim the foregoing as my own, I have hereto affixed my signature in the presence of two witnesses.

ERNEST F. RUECKERT.
